UNITED STATES PATENT OFFICE

169,751

MASSAGING MACHINE

Louis E. Holland, Lee's Summit, Mo.

Application August 30, 1952, Serial No. 21,264

Term of patent 14 years

(Cl. D83—1)

To all whom it may concern:

Be it known that I, Louis E. Holland, a citizen of the United States, residing at Lake Lotawana, Lee's Summit, in the county of Jackson and State of Missouri, have invented a new, original, and ornamental Design for a Massaging Machine, of which the following is a specification, reference being had to the accompanying drawing, forming a part thereof.

Fig. 1 is a perspective view of a massaging machine, showing my new design; and

Fig. 2 is a top plan view of the massaging machine.

The lower side and end walls not shown are substantially plain.

I claim:

The ornamental design for a massaging machine, as shown and described.

LOUIS E. HOLLAND,
